UNITED STATES PATENT OFFICE.

ELMER CLIFTON SHAVER, OF NEW YORK, N. Y.

STROPPING-MACHINE.

No. 850,974.

Specification of Letters Patent.

Patented April 23, 1907.

Application filed January 5, 1906. Renewed February 28, 1907. Serial No. 359,743.

To all whom it may concern:

Be it known that I, ELMER CLIFTON SHAVER, a citizen of the United States, residing at New York, in the county of New York and 5 State of New York, have invented certain new and useful Improvements in Stropping-Machines; and I do hereby declare the following to be a full, clear, and exact description of the invention, such as will enable 10 others skilled in the art to which it appertains to make and use the same.

My invention relates to stropping-machines; and its object is to provide a light and simple device of this character which can be 15 quickly placed upon a strop and which is particularly adapted for stropping razor-blades having handles connected to them, although, if preferred, the machine can be utilized for stropping blades of devices known 20 as "safety-razors."

The invention consists of a carriage having a blade-holder extending from side to side thereof and adapted to swing from side to side, said holder being actuated by a gear 25 which engages a rack connected to a handle to which the carriage is pivotally connected. The holder is so mounted and constructed that the blade of an ordinary razor or of a 30 safety-razor can be easily placed in engagement therewith and held thereby, and by pulling the carriage back and forth by means of the handle the holder will direct the blade downward upon the strop, so that the same will be drawn thereover with the carriage 35 and without injuring the strop.

The invention also consists of so disposing the handle that the strain will be evenly distributed over the strop and the carriage will be directed longitudinally thereon without 40 tending to twist or get out of place.

The invention also consists of certain other novel features of construction and combination of parts which will be hereinafter more fully described, and pointed out in the claims. 45 In the accompanying drawings I have shown the preferred form of my invention.

In said drawings, Figure 1 is a perspective view of my improved stropping-machine, the strop being shown by dotted lines and a 50 razor also being indicated by dotted lines in position upon the holder. Fig. 2 is a section through the machine and strop and showing the positions assumed thereby when the machine is traveling in the direction of the arrow, the blade of the razor also being shown in section; and Fig. 3 is a view similar to

Fig. 2, but showing the positions of the parts when the device is moving in a direction opposite to that indicated by Fig. 2, the direction of movement being shown by the arrow. 60

Referring to the figures by numerals of reference, 1 is a handle having a cross-strip 2 secured to one end, and disposed at one end of this strip is an ear 3, while at its other end is an arm 4, which terminates in an open 65 frame 5, the upper portion of which is toothed to form a rack 6. Pivoted to the ear 3 and to the lower portion of the arm 4 are arms 7, which extend downward from side plates 8. These plates and arms 70 constitute the sides of the carriage of the machine, and the two plates 8 are connected by rods 9, on which are disposed sleeves 10, which constitute rollers. Connecting the central portions of the plates 8 at their upper 75 edges is a rod 11, to which is permanently connected a clip 12, formed by bending a strip of sheet metal upon itself into substantially a U shape, and the sides of this clip taper toward each other, so as to firmly clamp 80 the blade 13 of a razor and hold it against displacement. One end of the rod 11 extends into the frame 5 and has a gear 14 fastened to it and which meshes with the rack 6. It will be noted that the upper edges of the 85 side plates 8 are recessed at opposite sides of the rod 11, and this is for the purpose herein-after more fully set forth.

In using the machine herein described a strop 15 is inserted between the cross-strip 2 90 and the rollers 10, and the razor-blade 13 is then inserted into the clip 12, so that its handle 16 will hang at one side of the strop, as shown by dotted lines in Fig. 1. It will be noticed that the handle 1 hangs directly 95 under the center of the strop, and therefore when the same is pulled backward and forward the carriage is moved evenly over the surface of the strop and will not twist the same. When the handle is drawn toward 100 the operator, as shown in Fig. 2, the frame 5 will be swung away from the operator and will cause the gear 14 to rotate so as to swing the blade upon the strop, as shown in Fig. 2. The carriage will therefore be drawn in the 105 direction of the arrow in said figure, and the edge of the razor will be carried over the surface of the strop. When it is desired to move the carriage in the opposite direction, the handle 1 is swung away from the operator, and this causes a prompt reversal of the 110 positions of the frame 5, gear 14, and holder

12, and all of the parts will assume the position shown in Fig. 3 during the movement of the carriage in the direction of the arrow in said figure.

5 While I have shown and described this machine for use in connection with the ordinary form of razor, it will be understood that it can also be utilized for stropping the blades of safety-razors. I attach considerable importance to the fact that the machine can be used for stropping both forms of blades.

Another important feature of this device is the fact that the holder 12 can be quickly raised out of contact with the strop, for the 15 reason that the rollers 10 travel upon the strop and there is nothing to prevent the holder from being lifted. The side plates 1 are recessed at their upper edges, as shown and described, so as to accommodate the 20 shank of a razor-blade, such as shown in Fig. 1, when the blade is turned from side to side. This is particularly desirable should the 25 strop be loose and necessitate the blade swinging below the level ordinarily required in order to come in contact with the strop.

Having thus fully described my invention, what I claim as new, and desire to secure by Letters Patent, is—

In a stropping-machine, the combination with a pair of plates and a depending arm 30 rigid with each plate; of a pair of rollers between said plates one at each end thereof, a blade-holder rotatably mounted between said plates, a gear at one end of said holder and integral therewith, a cross-strip below 35 said blade-holder, an ear at one end of said strip, an arm at the opposite end of said strip, means to pivotally secure said strip to the depending arms, a frame integral with the upper end of said arm, said frame having 40 an opening therein, a rack at the upper edge of said opening adapted to engage said gear and a depending handle secured to said strip.

In testimony whereof I have signed my name to this specification in the presence of 45 two subscribing witnesses.

ELMER CLIFTON SHAVER.
